(57) **CLAIM**

The ornamental design for an edgelit suspended luminaire, as shown and described.

DESCRIPTION

FIG. 1 is a perspective view of an edgelit suspended luminaire, showing our new design;

FIG. 2 is a bottom plan view thereof;

FIG. 3 is a top plan view thereof;

FIG. 4 is a left-side elevation view thereof;

FIG. 5 is a right-side elevation view thereof;

FIG. 6 is a front elevation view thereof; and,

FIG. 7 is a rear elevation view thereof.

The broken lines shown represent unclaimed subject matter and form no part of the claimed design. The curved broken lines shown passing through the design indicate the design is not limited to a single length and these lines represent unclaimed subject matter and form no part of the claimed design.
